UNITED STATES PATENT OFFICE

HARRY A. DOUGLAS, OF BRONSON, MICHIGAN

CIRCUIT-CONTINUING DEVICE

Application filed May 9, 1929. Serial No. 361,676.

My invention relates to devices that are inclusive of parts held in assembly by bayonet projections and channels.

The device of my invention is of particular service in connection with lighting outfits employing incandescent lamps and in which the lamps are adjustable to circuit opening and circuit closing positions while remaining in assembly. In such a structure I employ a gate which closes access to and from the bayonet channel to maintain the lamp in assembly. This gate is opened when it is desired to remove the lamp.

My invention is of particular service in connection with the structure disclosed in my copending application Serial No. 361,675, filed May 9, 1929, though the invention is not to be thus limited.

The invention will be more fully explained in connection with the accompanying drawing in which Fig. 1 is a side elevation illustrating the preferred embodiment of the invention, a portion being broken away and some parts being shown in section; Fig. 2 is a view taken at right angles to the direction in which Fig. 1 is taken, parts being shown in section; Fig. 3 is a sectional view on line 3—3 of Fig. 2; Fig. 4 is a sectional view on line 4—4 of Fig. 2; Fig. 5 is a sectional view on line 5—5 of Fig. 2; Fig. 6 is a view on line 6—6 of Fig. 2; and Fig. 7 is a fragmentary end view.

The structure illustrated is inclusive of a generally cylindrical shell 1 which is reduced at one end and there threaded to receive a nut 2 which is employed to clamp the shoulder 3 of the shell in assembly with a support 4, which support may be the dash-board of an automotive vehicle. The larger part of the casing may be surrounded by a finishing sheath 5. I have shown a distance preserving hollow washer 6 which may be interposed between the nut and the support. The shell constitutes a contact carrier to which end a contact carrier ring 7, of insulation, is assembled with the rear end of the shell. This ring of insulation is provided with a metallic bushing 8 that receives a metallic sleeve 9 which is slidable in the bore of the bushing. A circuit continuing conductor 10 enters the

sleeve 9 and is electrically connected with a contact button 11 at the inner end of the sleeve. A coil spring 12 surrounds the portion of the sleeve that is within the casing. One end of this spring presses against the bushing and the other end presses against the contact button whereby this button is forwardly pressed. The limit to which the button may be forwardly pressed is determined by the flange 13 which is provided upon the rear end of the sleeve 9, this flange being adapted for abutting engagement with the bushing. A contact 14, which is complementary to the contact 11, is provided upon a plug 15. This plug also constitutes a base of an incandescent lamp. A filament 16 of this lamp is located within the glass bulb 17 and has one terminal connected with the contact button 14. The other terminal of this filament is connected with a metallic sheath 15'. The lamp socket 18 is provided with diametrically opposite bayonet channels 19 which receive the bayonet pins or projections 20 that are provided upon and project laterally from the plug 15. These bayonet pins or projections are receivable at the front ends of the bayonet channels and pass along the bayonet channels longitudinally of the structure until the inner ends of the channels are reached whereafter the plug is turned to bring the said bayonet projections into the bayonet seats.

A coil spring 21 surrounds the lamp socket and is bottomed upon the shoulder 3. The outer end of the spring presses against the flange 22 which is formed upon the front end of the socket whereby the socket may be moved forwardly when the spring is permitted thus to function. When the socket is thus moved forwardly the contacts 11 and 14 are separated. When the socket is moved inwardly these contacts are engaged, the contact 11 then moving slightly to the rear against the force of the spring 12.

The socket 18 carries two diametrically opposite bayonet pins or projections 23 and the shell 1 is formed with two diametrically opposite bayonet slots or channels each having an entrance 24 extending along the structure and a transverse branch affording two seats 100

25 and 26 in which the corresponding bayonet pin or projection may be alternately received. The seats 25 are further forward than the seats 26, so that when the bayonet pins or 5 projections are within the former seats, the spring 21 is permitted to move the lamp socket forwardly to separate the contacts. When the bayonet pins or projections are within the inner seats 26, the socket is held 10 in an inward position against the force of the spring 21 to establish engagement between the contacts.

I provide an actuator for moving the lamp socket and the contact carrying base therein 15 to control the lamp circuit. This actuator is in the form of a generally cylindrical cowl 27 that has abutting and tight telescopic engagement with the lamp socket. To this end the lamp socket flange is formed with 20 rearward continuations that extend rearwardly and which are in the form of spring fingers 28 which, when free, expand at their tips beyond the diameter of the bore of the cowl so as to have tight engagement with the 25 cowl when the cowl is slipped in place. The cowl is formed with an internal bead 29 which has abutting engagement with the socket flange 22 to enable the cowl, when rearwardly pressed, to move the lamp socket and the 30 parts carried by the lamp sockets rearwardly against the force of the spring 21 to establish the lamp circuit. It was hitherto stated that one terminal of the filament 16 was connected with the contact button 14. The cowl is provided 35 with an opening 30 at its front end and in the region of the lamp bulb to enable the light to shine from the lamp to the cowl to the desired place that is to be illuminated. The cowl is desirably rotatable upon and with respect 40 to the socket to enable the opening 30 to be shifted to change the direction in which the light may emanate from the lamp. The front end of the cowl is desirably dome shaped to constitute a push button 31 by which the 45 cowl may be conveniently manipulated to establish the lamp circuit and to shift the direction in which the light is to shine.

In order to limit the extent to which the lamp socket may be forwardly projected by 50 the spring 21 when the cowl is removed, I provide a tongue 32 upon the shell and an opening 33 in the lamp socket, the rear border of this opening being engaged with the rear end of the tongue by the spring 21 when the 55 cowl is removed. In order to keep the lamp from rattling within its socket, I form the socket with an inwardly projecting spring tongue 34 which engages a side of the lamp.

The longitudinal branch 24 of one of the 60 bayonet channels in the shell 1 receives a gate 35 by which this channel branch or entrance portion is closed against the return thereto of the corresponding bayonet projection 23 after this projection has passed into 65 the generally transverse and seat bearing

portion of the channel. This gate is desirably a sliding bar that has one end received in the guiding groove 36 formed in the sheath 5, the other end of the gate being received in the bayonet groove. Groove 36 faces the 70 shell that cooperates with sheath to form this groove into a guiding socket for the gate. When the gate is in its innermost position, the corresponding bayonet channel is in its normal shape permitting the corresponding bayonet projection to be readily inserted and withdrawn. When the gate is moved to its outermost position, after the corresponding bayonet projection is seated, this bayonet 75 projection cannot be withdrawn, thus is the separation of the lamp socket from the shell prevented. One gate obviously serves to hold both bayonet projections 23 in assembly with the shell.

Having thus described my invention, I 85 claim:

1. The combination with a shell; of a socket surrounded by the shell and movable along the bore thereof; a spring pressing upon said socket; a plug within and carried by said socket; complementary contacts respectively disposed upon the plug and shell; a plunger carried by said socket and accessible for engagement at the front end of the shell whereby said socket may be inwardly moved 90 against the force of said spring, said socket and shell having interengaging bayonet projections and channel formations for holding the socket in position to maintain said contacts in engagement; a gate for closing the entrance portion of the bayonet channel; and a sheath for the shell and forming, with the shell, a guiding socket in which said gate is received.

2. The combination with a shell; of a 105 socket surrounded by the shell and movable along the bore thereof; a spring pressing upon said socket; a plug within and carried by said socket; complementary contacts respectively disposed upon the plug and shell; a 110 plunger carried by said socket and accessible for engagement at the front end of the shell whereby said socket may be inwardly moved against the force of said spring, said socket and shell having interengaging bayonet projections and channel formations for holding the socket in position to maintain said contacts in engagement; a gate movable within the entrance portion of the bayonet channel 115 to close the channel; and a sheath for the shell and forming, with the shell, a guiding socket in which said gate is received.

In witness whereof, I hereunto subscribe my name.

HARRY A. DOUGLAS.
